SLIP MOUNTING

Charles S. Crickmer, Dallas, Tex., assignor to
Merla Tool Company, Dallas, Tex., a firm

Application September 18, 1936, Serial No. 101,375

11 Claims. (Cl. 166—12)

This invention relates to new and useful improvements in slip mountings.

One object of the invention is to provide an improved slip mounting particularly adapted for use with a well packer or other similar tool.

An important object of the invention is to provide an improved slip mounting, including a plurality of flexible members which are so arranged that each member forms a link for carrying one of the slips, as well as a friction spring adapted to engage the well casing.

Another object of the invention is to provide an improved slip mounting which is so constructed that a link for carrying said slip and a friction spring for engaging the well casing below the slip, is formed of a single metallic member, the construction of the member being such that the friction spring may be damaged or broken without affecting the link connection for the slip.

A further object of the invention is to provide an improved member constructed of a spring metal or other flexible material for supporting a slip, which member is pivotally secured at its upper portion while its lower portion is free from positive connection, the upper end of said member being held in place by the pivotal connection, while its lower end is retained by the inherent tension or spring thereof, whereby a more simple and greatly improved linkage arrangement is had.

Still another object of the invention is to provide an improved slip mounting including, a sleeve slidable with relation to the gripping slips, together with a plurality of spring members for connecting the sleeve and slips and also for providing friction springs for engaging the well casing, one of said members being provided for each slip and each member being constructed so that its upper portion forms a reinforced and rigid link for securing the upper end of the sleeve to the slip, the lower portion of the member being curved or bent in a long arc substantially throughout the vertical length of the sleeve and having its extreme lower end connected with the sleeve, whereby an elongate friction spring for engaging the well casing is formed by the lower portion of each member.

A still further object of the invention is to provide a link member which serves not only to support the slip, but is so constructed that it tends at all times to urge the slip into its retracted position.

Another object of the invention is to provide an improved slip mounting which is so con-

structed that the links for carrying the slips are pivotally connected to said slips and a supporting sleeve, the links being extended beyond the pivotal connection to the supporting sleeve to form a flexible member which is maintained under tension, thereby tending at all times to urge the slips into their retracted position, which arrangement reduces the possibility of damage or breakage of the connecting links; and having friction spring members provided on the supporting sleeve, and independent of the slip carrying links, for engaging the well casing.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is a view partly in elevation and partly in section showing the upper portion of a slip mounting constructed in accordance with the invention.

Figure 2 is a continuation of Figure 1 showing the lower portion of the slip mounting.

Figure 3 is a horizontal, cross-sectional view taken on the line 3—3 of Figure 1.

Figure 4 is a horizontal, cross-sectional view taken on the line 4—4 of Figure 2.

Figure 5 is a view partly in elevation and partly in section of a modified form of the invention, and

Figure 6 is a horizontal, cross-sectional view taken on the line 6—6 of Figure 5.

In the drawings, the numeral 10 designates an elongate tubular mandrel which has a recovery ring 11 secured thereon, the ring being preferably made integral therewith. A slip head or cone 12 surrounds the mandrel, being slidable thereon, and has its lower end resting on the ring 11 whereby the cone is supported by said ring. A suitable packing member 12' is carried by the upper end of the cone 12, said packing member being provided with a flanged cap 12a for holding the packing member in position around the mandrel 10. A coupling collar 10' is carried by the upper end of the mandrel 10 and has an annular member 12b secured to its lower end which member is adapted to engage the flanged cap 12a at the upper end of the packing member.

An elongate sleeve 13 is slidably mounted upon the mandrel 10 below the cone 12 and the ring 11 and is provided with diametrically opposite J-slots 14. The mandrel has a pair of ra-

dially extended pins 15 which normally engage in the horizontal portions or legs of the J-slots 14, as clearly shown in Figure 1. The pins and slots serve to connect the mandrel and sleeve together, 5 whereby when the mandrel is moved, the sleeve moves therewith.

With the pins in the horizontal legs of the slots, the upper end of the sleeve is spaced from the ring 11. This upper end of the sleeve is enlarged to form a head 16 which is provided with a plurality of vertical slots 17, while the lower end of said sleeve is formed with an enlarged collar 19 having a plurality of slots 18 therein.

A plurality of arcuate slips 20 are slidable on 15 the exterior surface of the cone 12 and when the slips are at the lower end of the cone, as shown in Figure 1, said slips are retracted or disengaged from the wall of the well casing A. It will be obvious that when the cone is moved downwardly with relation to the slips, said slips will be moved radially due to the incline of said cone. The radial expansion of the slips 20 causes the teeth on their outer faces to engage or grip the inner wall of the casing.

25 For supporting the slips in position on the cone, and for connecting the slips with the sleeve 13, a plurality of flat spring members 21 are provided, one for each slip. The upper portion of each spring member 21 extends within the slot 17 30 of the sleeve head 16, and is engaged around a transverse pin 22, which is secured in said head and which extends across the slot. One end of each spring member is located at a point immediately below the pin 22 and extends upwardly 35 forming a loop 22' around said pin from which it further extends upwardly into a recess 23 provided in the rear face of each slip. The spring member is then bent upon itself to form an eye 24', through which a transverse pin 24 extends. 40 The pin 24 is secured in the slip and extends across the recess 23, and thus, it will be seen that the slip is pivotally connected with the member.

From the pin 24, the spring member extends downwardly into the slot 17 with its outer flat 45 surface engaging the inner flat surface of the upwardly extended portion, whereby the two engaging surfaces may be welded, or otherwise secured together, thereby forming a link B between the sleeve 13 and the slip 20, said link being pivotally connected to both the sleeve and the slip. 50 The spring member 21 is constructed of a metal having a certain amount of inherent resiliency, and by constructing each link of a double thickness of said metal the link is made substantially 55 rigid, whereby it has sufficient strength to carry the weight of the slip.

The lower end of each slot 17 of the sleeve 13 is bevelled or inclined as at 17' and the spring member 21 extends downwardly from the pin 22 60 and bears against this inclined surface. From the surface 17', the member is curved outwardly in a long arc, the central portion of which engages the wall of the well casing A, as shown in Figure 2. The lowermost end of the spring member is confined within the slot 18 provided within the collar 19 at the lower end of the sleeve. It will be obvious that, due to the resiliency or flexibility of the member, the curved portion of said member between the slots 17 and 18 forms a friction 65 spring C, which is in constant engagement with the casing A.

It is noted that the link B and the friction spring C are formed of a single spring member 21 and are so arranged that the friction spring C 70 may wear out or break without interfering with

or producing a counter-effect upon the slip mounting. It is further noted that pivoting the spring member at its center gives a superior linkage arrangement to the old method of using link ears and bolts to connect the slip with the sleeve, 5 since any strain to which the linkage is subjected is distributed over the entire spring member and not concentrated upon any single part. It is also noted that, due to the pivotal connection of the link B with the spring 21 at the lower end of the 10 link B, since the spring member 21 is maintained under tension by the bevelled end of the slot 17' the portion of the linkage below the pin 22 is urged outwardly while said pin acts as a fulcrum and the link B is urged inwardly therefore and 15 tends to press the slips inwardly toward their retracted position.

In operating the device, the mandrel 10 is lowered into the well casing A to any desired depth with the slips 20 held in their retracted position 20 by the tension in the springs 21 acting through the links B which are secured to the sleeve 13, which sleeve is connected to the mandrel by the pins 15 and slots 14.

When it is desired to set the slips, the mandrel 25 is rotated in a counter-clockwise direction and the radial pins 15 slid laterally within the horizontal legs of the J-slots 14, while the sleeve 13 is held in a stationary position by the friction springs C engaging the casing wall A under tension. 30 At this time, the slips being connected to the sleeve by the links B, are also held stationary.

This rotation permits the mandrel to descend through the sleeve 13 as the pins 15 slide within the vertical position of the J-slots 14. As the 35 mandrel moves downwardly, the member 12b engages the cap 12a on the packing member and acting through said packer, moves the cone 12 downwardly within the slips while said slips are held stationary, thereby expanding the slips radially into gripping engagement with the casing wall. 40 By the time the mandrel has moved downwardly a sufficient distance to fully expand the slips, there will be a clearance between the ring 11 and the cone 12, whereby the weight of the 45 mandrel is exerted through the packer upon the cones and slips, and said slips grip the wall of the casing to support the cone, packer and mandrel. Of course, continued movement of the mandrel will set the packer in the usual manner. 50

When it is desired to remove the device from the well to reset the slips, the mandrel is raised and turned in a clockwise direction to re-seat the pins 15 in the lateral leg of the J-slots. The pressure on the packer is thereby released and said 55 packer, due to its resilient nature, will return to its retracted position. The ring 11 on the mandrel will ascend therewith and carry the cone 12 upwardly, thereby disengaging the slips 20 from the casing wall by permitting the spring members 60 21 to move the slips inwardly to their retracted position. Thus, the sleeve 13 is again connected to the mandrel and will be lifted therewith.

A modified form of the slip mounting is shown in Figures 5 and 6, in which the slips 20 are 65 mounted in the same manner as has been hereinbefore described, having the resilient members 21 forming connecting links between the pins 22 in the slips and the transverse pins 22 in the upper end of the sleeve 13, whereby substantially 70 rigid connecting links B are formed. The spring members extend downwardly from the pins 22 and bear against the inclined surface of the slots 17 as has been described, but, instead of being 75 extended further downward to form the friction

springs C, said spring members are cut off just below the surface 17' of the slots.

Individual friction springs C' are mounted on the sleeve 13, each spring having its upper end pivoted by means of a pin 30 within a slot 29 provided in the sleeve head 16. The springs C' are curved in a long arc and have their lower ends engaged in slots 18 in the collar 19 at the lower end of the sleeve as has been previously described. It is noted that the friction springs C' are offset out of alignment with the links B and are alternately placed with said links about the periphery of the sleeve head 16 as is clearly shown in Figures 5 and 6.

The advantages of this form of the invention are that the links B and the friction springs C' may be made and mounted separately, whereby a heavier material may be used for the springs C than is used and necessary in the linkage B, and a resultant longer wear of the friction springs C obtained than if the same material were used throughout. It is noted that the action of the links B is the same in this form as in that first described, the difference being in making and mounting the friction springs separate from said links.

It is understood that, while a packer element has been described, in conjunction with the slip mounting, the invention rests in the slip mounting itself and any other desired element or tool may be used therewith.

What I claim and desire to secure by Letters Patent is:

1. A slip mounting including, a support having gripping slips slidably mounted thereon, a movable member mounted on the support below the slips, links connecting the slips and member, each link having its upper end pivoted to one of the slips, its central portion pivoted to the upper end of the movable member and its lower end engaging the side of said member, and friction springs on the member below the links.

2. A slip mounting including, a support having gripping slips slidably mounted thereon, a movable member mounted on the support below the slips, links connecting the slips and member, each link having its upper end pivoted to one of the slips, its central portion pivoted to the upper end of the movable member and its lower end engaging the side of said member, friction springs on the member below the links, means for connecting the movable member to the support whereby the slips are maintained in a fixed position with relation to the support, means for disconnecting said movable member whereby the support may move with relation to the slips, and means carried by the support for radially expanding the slips upon such movement of the support.

3. A slip mounting including, a support having gripping slips slidably mounted thereon, a movable member mounted on the support below the slips, links connecting the slips and member, each link having its upper end pivoted to one of the slips, its central portion pivoted to the upper end of the movable member and its lower end engaging the side of said member, friction springs on the member below the links, means for connecting the movable member to the support whereby the slips are maintained in a fixed position with relation to the support, means for disconnecting said movable member, the friction springs on the movable member acting to hold the movable member stationary when said member is disconnected from said support, whereby

the support may move with relation to the slips and means carried by the support for radially expanding the slips upon such movement of the support.

4. A slip mounting including, a support having gripping slips slidably mounted thereon, a movable member mounted on the support below the slips, links connecting the slips and member, each link having its upper end pivoted to one of the slips, its central portion pivoted to the movable member and its lower end engaging the side of said member, the linkage being constructed of a resilient material whereby the slips are urged inwardly toward their retracted position at all times due to the pivotal arrangement, friction springs on the member below the links formed by extending the slip supporting links downwardly and outwardly in a long arc, said links and springs being formed in a single piece, means for connecting the movable member to the support whereby the slips are maintained in a fixed position with relation to the support, means for disconnecting said movable member, the friction springs on the movable member acting to hold the movable member stationary when said member is disconnected from said support, whereby the support may move with relation to the slips, and means carried by the support for radially expanding the slips upon such movement of the support.

30

5. A slip mounting including, a support having gripping slips slidably mounted thereon, a movable member mounted on the support below the slips, links connecting the slips and member, each link having its upper end pivoted to one of the slips, its central portion pivoted to the movable member and its lower end engaging the side of said member, and friction springs on the member separate from and individually mounted below the links.

40

6. A slip mounting including, a support having gripping slips slidably mounted thereon, a movable member mounted on the support below the slips, links connecting the slips and member, each link having its upper end pivoted to one of the slips, its central portion pivoted to the movable member and its lower end engaging the side of said member, and friction springs on the member separate from and individually mounted below the links, the springs being located in staggered relation to the links in a vertical plane.

50

7. A slip mounting including, a support having gripping slips slidably mounted thereon, a movable member mounted on the support below the slips, links for connecting the slips and the movable member, each link having its upper end pivoted to one of the slips, its central portion pivoted to the upper end of the movable member and its lower end engaging the side of the member, said link being formed of a continuous piece of resilient material bent upon itself to provide a substantially rigid and friction spring on the member below the links.

55

8. A slip mounting including, a support, gripping slips slidably on the outer surface of the support, and a supporting member for each slip having a pivotal connection with the slip, said connection being arranged to permit said slip to swing on said member in a direction radially of the support, each supporting member having its lower portion bowed outwardly to form an elongate friction spring.

60

9. A slip mounting including, a support, gripping slips slidably on the outer surface of the support, a supporting member for each slip hav-

75

- ing a pivotal connection with the slip, said connection being arranged to permit said slip to swing on said member in a direction radially of the support, each supporting member having its lower end bowed outwardly to form an elongate friction spring, and means slidable on the support and having each supporting member secured thereto, whereby said means and slips are fastened together by the members.
10. A slip mounting including, a support, gripping slips slidable on the outer surface of the support, a supporting member for each slip having a pivotal connection with the slip, said connection being arranged to permit said slip to swing on said member in a direction radially of the support, each supporting member having its lower end bowed outwardly to form an elongate friction spring, means slidable on the support and having each supporting member secured thereto, whereby said means and slips are fastened together by the members, means for connecting the slidable means to the support whereby the slips are maintained in a fixed position with relation to the support, means for disconnecting said slidable means, whereby the support may move with relation to the slips, and means car-
- ried by the support for radially expanding the slips upon such movement of the support.
11. A slip mounting including, a support, gripping slips slidable on the outer surface of the support, a supporting member for each slip having a pivotal connection with the slip, said connection being arranged to permit said slip to swing on said member in a direction radially of the support, each supporting member having its lower end bowed outwardly to form an elongate friction spring, means slidable on the support and having each supporting member secured thereto, whereby said means and slips are fastened together by the members, means for connecting the slidable means to the support whereby the slips are maintained in a fixed position with relation to the support, means for disconnecting said slidable means, the friction springs formed by the members and secured to the slid-
able means acting to hold the sleeve stationary when said sleeve is disconnected from said support, whereby the support may move with relation to the slips, and means carried by the support for radially expanding the slips upon such movement of the support.

CHARLES S. CRICKMER.
